CLARENCE SCHOFF, OF TEHACHAPI, CALIFORNIA.

WINDMILL ATTACHMENT.

1,274,569.

Specification of Letters Patent. Patented Aug. 6, 1918.

Application filed December 4, 1917. Serial No. 205,407.

To all whom it may concern:

Be it known that I, GEORGE W. LOVEJOY, a citizen of the United States, residing at Tehachapi, in the county of Kern and State 5 of California, have invented a new and useful Windmill Attachment, of which the following is a specification.

This invention relates to windmill or pump attachments and particularly to improvements in that class of attachments known as equalizers.

As is well known, the common windmill pump while satisfactory enough in operation during strong winds, is very unreliable when 10 light variable winds prevail. This inherent disadvantage in windmills has been overcome in part by various attachments known in the art as "equalizers", usually expansible coiled springs. These springs may be 15 mounted on the pump-rod concentric with the same and may bear at one end against a stationary collar, attached to the windmill power, while the other end may be fixed to the pump-rod itself or may bear 20 against a collar secured to the pump-rod. As their name indicates, the "equalizers" tend to make equal the resistance of the downstroke and the up stroke of the pump by storing up energy on the down stroke 25 30 when they are compressed, and by giving out energy on the up stroke, when they expand.

The reason why equalizers are necessary is because on the up stroke of the pump the 35 windmill must not only lift the water but the weight of the pump-rod, the valve, etc., as well as overcome friction, while on the down stroke of the pump the weight of the pump-rod, etc., aids the stroke, and only 40 friction impedes the motion. By utilizing the surplus energy of the down stroke to compress a spring, the up stroke will have available the power lent by the expansion of said spring. Thus the "equalizer" lives 45 up to its name and allows the windmill to run smoothly and without pauses in lighter winds than would be required to operate it ordinarily.

Now, an equalizer attached to a windmill 50 as outlined above has been found to give satisfactory results for a while; but in the course of time, the spring, even if frequently oiled, will heat and go dry and quickly rust. Then it will cut on the rod and break. If

one attempts to prevent the wear by making 55 the spring fit very loosely on the rod, the spring will get out of true and in time break at the point of greatest strain.

It is the general object of this invention to provide an equalizer which will be rust- 60 proof and practically wear-proof. To be more specific, it is my object to provide an equalizer which will work in a bath of oil.

Other objects are to make an equalizer which will be to a high degree adjustable, 65 which will give good service, and which may be put on a windmill in a short time by a mere novice.

The invention will be explained in the 70 specific description following.

Reference is to be had to the accompanying drawing forming a part of this specification, in which similar characters of reference indicate corresponding parts in all 75 views.

In the accompanying drawing: 80 Figure 1 is a fragmentary side elevation of a windmill showing the device constructed in accordance with the invention applied; Fig. 2 is an enlarged fragmentary vertical sectional view through the device;

Fig. 3 is a sectional view on the line 3—3 of Fig. 2 looking in the direction of the arrow.

Referring to the drawing in detail, the 85 device comprises a coiled expansion spring 5 which is disposed exteriorly of and surrounds a pump rod 6 of the ordinary or any preferred construction, the spring being disposed between an adjustable collar and the 90 base of an oiler, the details of which will be hereinafter fully described.

The oiler comprises a base plate 7 which is bolted or otherwise fastened to a stationary part of the windmill tower frame, and 95 is provided with a suitable opening through which is passed the pump rod 6 for reciprocation in the operation of the pump. Formed on the plate 7 and depending therefrom coaxially of the opening for the pump 100 rod 6 is an externally threaded gland or boxing 8, and adjustably engaged therewith is a hollow nut 9 in which is held a packing 10. The packing 10 acts against the outer end of the gland or boxing 8 and on adjustment of the nut 9 it can be compressed about the pump rod.

Formed on the base plate 7 at the upper

- side thereof concentrically of the opening through which works the pump rod 6 is an externally threaded nipple or annular flange 11 to which is engaged a barrel or cylinder 12. This barrel or cylinder 12 constitutes an oil top or container, and being internally threaded as shown in Fig. 2, is adapted to screw down upon the nipple or flange 11 until its lower edge comes in contact with the plate 7. Oil, as designated by the numeral 13, is poured into the upper open end of the barrel, thus providing means for lubricating the rod and the spring as will be explained.
15. The spring 5 has its lower end seated on the base plate 7 within the flange or nipple 11, and on the down stroke of the pump rod 6 the spring is compressed within the barrel or cylinder 12 which contains oil, so that the coils of the spring will be thoroughly lubricated. On the up stroke of the pump-rod, the coils of the spring will lift during its expansion and will carry along a coating of oil. This coating not only practically eliminates heating and consequent wear between the pump-rod and spring, but enables the spring to fit closely to the rod, thereby doing away with any possibility of kinking.
30. The adjustable collar hereinbefore mentioned comprises a split sleeve formed of the separable parts 14, each provided with outwardly extending ears 15. Each of these ears is provided with a tapped hole, and screws or bolts 16 pass through these holes and firmly clamp the parts 14 together. The pump-rod is provided along a portion of its length with screw threads 17, while the bore of the collar is similarly threaded internally, so that the collar may be moved up and down on the rod at will. The purpose of the collar is to provide adjusting means for the spring, and in order to fulfil its function, its lower end has a counter-seat 18 to bear against the upper end of the spring. When the latter loses some of its power, the collar may be screwed down to bear harder against the spring, thus making up for this loss of strength.
45. The packing in the hollow nut 9, which is internally threaded and adjustably engaged on the gland or boxing 8, will prevent the leakage of the oil from the cup 12 downwardly upon the rod 6 as will be apparent.
55. It will be obvious that the spring 5 will be thoroughly lubricated in the working of the pump rod 6, as the entire length thereof will be compressed within the body of oil 13 contained in the cup 12 on the down stroke of the rod. Upon the up stroke the spring will act as an oil distributer, and will keep the rod constantly bathed with lubricant.

From the foregoing, it is thought that the construction and the manner of operation of

the equalizing device will be understood, and therefore a more extended explanation has been omitted.

What is claimed is:

1. In a pump structure, a movable pump rod, an equalizer device operative upon the rod, and a lubricant container fixed relatively to the rod and adapted to receive the equalizer device for lubricating the same upon movement of the pump rod. 70
2. In a pump structure, a movable pump rod, an equalizer device operative upon the rod, a lubricant container fixed relatively to the rod and adapted to receive the equalizer device for lubricating the same upon movement of the pump rod, and means on the pump rod for adjusting the equalizer device. 75
3. The combination with a support, of a reciprocating rod in said support, a stop on the rod, a lubricant container on the support and surrounding the rod, and a coiled expansion spring surrounding the rod and having its bearing against the stop and interiorly of the container and adapted to be compressed within the latter for the lubrication of said spring, the rod being lubricated upon the expansion of the spring. 80
4. The combination with a support, of a reciprocating rod in said support, a stop on the rod, a lubricant container on the support and surrounding the rod, a coiled expansion spring surrounding the rod and bearing against the stop and also the interior of the container and adapted to be compressed within the latter for the lubrication of said spring, the rod being lubricated upon the expansion of said spring, said lubricant container having a packing gland at its lower end surrounding the rod. 85
5. The combination with a support, of a reciprocating rod in said support, a stop on the rod, a lubricant container surrounding the rod, said container having a base secured to the support and a packing gland at its lower end surrounding the rod with an oil tight packing within said gland, a coiled expansion spring surrounding the rod and bearing against the stop and also interiorly of the container and adapted to be compressed within the latter for the lubrication of said spring; the rod being lubricated upon the expansion of said spring. 90
6. The combination with a support, of a reciprocating rod in said support, a stop on the rod, said rod being externally threaded and said stop being internally threaded whereby it may be adjustably connected to the rod, a lubricant container surrounding the rod, said container having a base secured to the support and a packing gland at its lower end surrounding the rod with an oil tight packing within the gland, and a coiled expansion spring surrounding the rod and bearing against the stop and also in- 95

teriorly of the container and adapted to be compressed within the latter for the lubrication of said spring, the rod being lubricated upon the expansion of said spring.

- 5 7. In a pump, a frame, a pump rod movable in the frame, a self-lubricating equalizer secured to the frame, said equalizer comprising a base plate having a passage for said pump rod, an externally threaded 10 packing gland depending from the base plate and surrounding the pump rod, a hollow nut adjustably engaging the threaded packing gland and having packing therein, a nipple portion rising from the base plate

and surrounding the rod, an oil container 15 screwed upon said nipple portion and open at its upper end, a stop on said rod, a spiral spring mounted on the rod with one end engaged in the nipple and the other engaged with said stop, and means for adjusting the 20 position of the stop on the rod.

In testimony that I claim the foregoing as my own, I have hereto affixed my signature in the presence of two witnesses.

GEORGE WALTER LOVEJOY.
